United States Patent Office

Des. 178,420
Patented July 31, 1956

178,420

FILLING STATION UNIT

David Gregory Norris, Shreveport, La., assignor to The
J. B. Beard Company, Inc., Shreveport, La., a corpora-
tion of Delaware

Application February 14, 1956, Serial No. 40,163

Term of patent 14 years

(Cl. D13—1)

Fig. 1.

Fig. 2.

Figure 1 is a front elevational view of a filling station unit of my new design; and

Figure 2 is a top plan view thereof.

Three sides of the lower portion of the filling station unit shown are similar to the side shown, the other side being plain.

I claim:

The ornamental design for a filling station unit, sub-
stantially as shown and described.
